SETH WAY, OF LA PORTE, INDIANA.

Letters Patent No. 84,449, dated November 24, 1868.

IMPROVEMENT IN CULTIVATORS.

The Schedule referred to in these Letters Patent and making part of the same.

To all whom it may concern:

Be it known that I, SETH WAY, of La Porte, in the county of La Porte, and State of Indiana, have invented a new and useful Improvement in Cultivators; and I do hereby declare that the following is a full, clear, and exact description of the same, reference being had to the annexed drawings, making a part of this specification, in which—

Figure 1 is a plan view of my improved cultivator, and

Figure 2 is a side elevation of the same.

Corresponding letters refer to corresponding parts in both figures.

The object of this invention is an improvement in cultivators; and

It consists, first, in a swivelling joint attached to the tongue of the carriage, and to which the forward end of the plow-beams is attached; and

It further consists in a peculiarly-formed lever, for raising and lowering the plows and their beams; and

It further consists in a stirrup which passes over and embraces the double plow-beams, and by which their position with reference to each other is regulated; and

Lastly, it consists in a device, by which the tongue is secured to the axle.

A is the tongue of the carriage, to which the forward ends of the plow-beams are secured, by means of the swivel-joint hereafter to be described.

B are the wheels, which are of the usual construction.

C is the double-tree, which is of peculiar construction, it being composed of two bars or parts, of equal length and width, running parallel with each other, but having a washer between them, in their centres, of sufficient thickness to insure their being kept a distance apart sufficient to allow the inner ends of the single-trees to pass between them, by which arrangement I am enabled to provide for attaching four horses, should it become necessary.

D are the levers of the plows, which consist of two bars of wood, of sufficient length, width, and thickness, the two being jointed together, at their front ends, by a bolt, which passes through them and through the lower end of the rod or bar, which forms a portion of the swivel-joint above referred to. From this point, each of these beams, or such portion of what may be termed a double beam, diverges from the other at an angle sufficient to give the required distance between the plows which are placed thereon.

E are the handles of the plows, which are of the usual construction, and are secured to the beams in the usual manner.

F are the standards, the upper ends of which are bolted or otherwise secured to the plow-beams, and to the lower ends of which the shovels are secured. In addition to the above, these standards are provided with a brace, 6, the lower end of which is provided

with a series of holes for the reception of a bolt, which passes through said brace and through the standard, by which means the angle of such standard, as well as the depth to which the plow enters the earth, can be regulated, the upper ends of such braces being secured to the beams of the plow.

1 is a lever, for raising the plows and their beams clear of the ground, when it becomes desirable to do so.

This lever is of peculiar construction, it consisting of two portions, which are nearly at a right angle to each other, and yet varying from such an angle, as will now be described.

The long arm of this lever is of suitable length to enable the driver to raise and lower the plows with ease, and is secured to the tongue, at the proper point, by means of a bolt, upon which it turns, and which forms its fulcrum. From one side of this lever, and at a point opposite such fulcrum, extends an arm, at such an angle that when the long arm assumes a horizontal position, which, as shown in fig. 2, is when the plows are in their working position, the short arm will stand slightly back of a line drawn through its centre of rotation; the object of this arrangement being, that when the long arm of the lever is thrown back upon the axle, for the purpose of raising the plows, a portion of their weight shall be caused to rest upon said long arm of the lever, to prevent its being displaced while the machine is being transported from place to place.

2 is a socket, which is secured to the tongue of the carriage by means of a bolt; said sockets having flanches, which embrace the upper and lower edges of said tongue. Passing vertically through this socket, is a rod, which has a nut upon its upper end, which rests upon said socket, and carries the forward ends of the plow-beams, and as said rod turns freely within the socket, it permits of the required amount of lateral motion being given to the rear end of the plow-beams.

3 are sockets, which are placed upon the ends of the wooden portion, 7, of the axle, which sockets have formed upon their upper sides, and near their inner ends, additional sockets, for the reception of the ends of the tongue A, which are secured therein by means of keys driven through said sockets and above the tongue.

In order that the metallic and wooden portions of the axle and tongue may be firmly secured together, the socket which receives the axle, has a portion of its upper surface cut away, where the tongue passes through or across it, by which means, as the tongue is passed through its socket, it enters a recess in the top of said axle, and as the key is driven home, the three parts are bound firmly together.

4 are clamps of metal, which embrace the two sections of each of the plow-beams in the rear of the handles, and as these portions of the beams are constantly diverging from each other, it follows, that, as these clamps are pressed or driven backward, the diverging ends are brought nearer to each other, by which means

the distance between the plows or shovels, which are attached to said sections of the beams, is regulated.

5 is the hanger, which extends from the elevating-lever 1 to the plow-beams.

Having thus described my invention,

What I claim, and desire to secure by Letters Patent, is—

1. The swivelling joint 2 8, secured to the tongue of the carriage, substantially as and for the purpose described.

2. The construction of the lever 1, and its combination with the plow-beams, substantially as shown and described.

3. The arrangement of the stirrups 4, with reference to the two diverging portions of the plow-beams, substantially as and for the purpose described.

4. The socket 3, and its combination with the axle 7 and tongue A, substantially as shown and described.

In testimony whereof, I have signed my name to this specification, in the presence of two subscribing witnesses.

SETH WAY
